CONTAINER

Anthony P. Costa and Joseph Costa, Jr.,
Athens, Ga.

Application February 18, 1937, Serial No. 126,485

2 Claims. (Cl. 229—51)

This invention relates to the class of paper receptacle and has particular reference to the type of container or paper receptacle employed for holding ice cream, frozen confections and the like.

The carton or receptacle of the present invention is provided in a manner to facilitate the packing of ice cream or frozen confection and to dispense with the need of a spoon for 10 eating the contents of the container or carton.

The present invention involves certain new and useful improvements over the container forming the subject matter of our prior Patent No. 2,070,711, granted on Feb. 16, 1937.

The present invention together with its objects and advantages will be best understood from a study of the following description taken in connection with the accompanying drawings wherein:

20 Figure 1 is an elevational view of one side of the container.

Figure 2 is a side elevational view of the container taken at right-angles to Figure 1.

Figure 3 is a top plan view.

25 Figure 4 is a detail view showing the manner of removing successive portions of the container.

Figure 5 is a vertical sectional view through the lower portion of the container with upper parts of the container having been removed.

30 Figure 6 is a bottom plan view of the container and

Figure 7 is a plan view of the blank from which the container is formed.

Referring to the drawings by reference numerals it will be seen that the container is of 35 elongated form, substantially rectangular in cross section. In accordance with the present invention the container comprises four elongated sides or walls 1, 2, 3 and 4.

40 Walls 1 and 4 at their meeting edges are joined through the medium of a longitudinal flap 5 provided on the longitudinal edge of the wall 1 and adhesively secured to the inner surface of the wall 4.

45 The lower portions of walls 2 and 4 converge and the lower portions of walls 1 and 3 are folded on lines 6, 7, inwardly between the lower portions of walls 1 and 4 and the lower portions of the walls 1, 2, 3 and 4 are held in their final 50 position by being adhesively united adjacent their lower edge portions as at 8. It will thus be seen that the lower portions of the walls form a tapered handle for the container and also provide a closed bottom for the container.

55 Walls 2 and 4 at their upper end edges are pro-

vided with integral closure flaps 9 that are foldable inwardly one upon the other, while walls 1 and 3 are provided respectively with flaps 10, 11, respectively which are foldable one upon the other and upon the folded flaps 9.

Flap 11 is provided with a tongue 12 to engage a slit 13 provided in the flap 10 for securing all the flaps 9, 10 and 11 in folded position for sealing or closing the top or upper end of the container.

To facilitate removal of portions or sections of the container, successively, and as the ice cream or frozen confection contained therein is consumed, the walls 1 to 4 inclusive together with flap 5 are transversed at vertically spaced points 15 in their length by score lines 14, while one of the walls, for example the wall 2 is provided with diagonal score lines 15 arranged in alternation to the score line 14.

Further, in accordance with the present invention at the fold line between two integral walls, in the present instance walls 2 and 3, the blank is scored on short score lines 16 that merge with the score lines 15.

It will thus be seen that when it is desired 20 to remove, for example the portion of the container above the uppermost score line 14, the container is first torn along the uppermost vertical score line 16, and then by tearing along the uppermost diagonal score line 15 and the uppermost horizontal score line 14 the portions of the walls 1 to 4 inclusive and the flap 5 above the uppermost score line 14 are removed.

It will thus be seen that in a similar manner 35 each successive section or portion of the container may be removed by tearing first along a score line 16, then along a diagonal line 15 and finally along a horizontal score line 14.

In actual practice, and as shown in Figure 7, the container is formed from a single blank of 40 strong, comparatively stiff paper suitably treated, and cut to the blank form suggested in Figure 6. The walls 1 to 4 inclusive and flap 5 are formed by folding the blank on longitudinal, parallel, fold lines 17, while the lower portions of the walls 1 to 4 inclusive, and flap 5, are bendable on a horizontal fold line 18, and the flaps 9, 10 and 11 are bendable on the horizontal or transverse fold line 19.

By adhesively uniting the lower portions of the walls 1 to 4 inclusive for sealing the lower end of the container the use of a flap such as provided in the container forming the subject matter of our co-pending, and hereinbefore referred to appli- 55

cation for patent for providing a closed bottom for the container is dispensed with.

Also by, in accordance with the present invention, having the diagonal score lines 15 arranged as shown and by the addition of the vertical score lines 16 the removal of successive portions of the container may be more readily and easily effected, the score lines 16 rendering more easy the initial tearing or scoring of the blank incidental to removing a section of the container.

10 A feature of a container embodying the principles of the present invention is the collapsibility of the lowermost and remaining section of the container which collapsibility facilitates ejecting from the bottom of the container any ice cream or part of the frozen confection that might otherwise accumulate therein and be more or less inaccessible except by a complete destruction of the lowermost portion of the container.

15 20 It is thought that a clear understanding of the construction, utility and advantages of a container of this character will be had without a more detailed description.

Having thus described our invention, what is 25 claimed as new is:—

25 1. A container of the class described formed of destructible material having side walls closed at the bottom thereof, horizontal score lines extending transversely of the walls at vertically spaced

points thereon, and diagonal score lines arranged on one of said walls in alternation to said horizontal score lines and respectively extending from one score line to terminate at one edge of said wall at a point midway between two adjacent horizontal score lines and vertical score lines connecting the diagonal score lines with the horizontal score lines to provide an uninterrupted score line extending throughout said wall.

2. A container of the class described formed of 10 destructible material having side walls closed at the bottom thereof, horizontal score lines extending transversely of the walls at vertically spaced 15 points thereon, and diagonal score lines arranged on one of said walls in alternation to said horizontal score lines and respectively extending from one score line to terminate at one edge of said wall at a point midway between two adjacent horizontal score lines, and vertical score lines at the line of fold between said one wall and a second 20 integral wall of the container and terminating at the upper ends of the diagonal score lines to facilitate initial tearing incidental to a removal of a portion or section of the container, said horizontal, diagonal and vertical score lines being 25 uninterrupted throughout said wall.
